UNITED STATES PATENT OFFICE

WILHELM SCHMIDT, OF PEINE, GERMANY, ASSIGNOR TO THE FIRM GEBR. KARGES,
OF BRUNSWICK, GERMANY

TRANSPORTING VESSEL

Application filed August 28, 1929, Serial No. 389,042, and in Germany January 18, 1927.

This invention relates to transporting vessels, such as are used in preserving factories and the like for transporting and temporarily storing vegetables, fruit and the like. According to the invention such a vessel is so constructed that the material to be treated can also be boiled, cooled, washed, dyed and subjected to other operations, without the necessity of transferring it from one vessel to another between two operative stages. This signifies a considerable saving in work, which is of importance for preserving factories having seasonal rush periods, and prevents damage to the material which is very apt to suffer seriously through being transferred from one vessel to another. This also reduces the number of vessels used and the number of hands employed. The new vessel forms a freely movable pail or similar container capable of being inserted into any boilers, washing troughs, dyeing vats or the like and having a perforated bottom through which the boiling, washing or dyeing medium can enter, which, rising from below, passes through the contents of the vessel and can pass out again through perforations or the like at the top.

A further feature of the invention is a trough or the like, which is provided with means for sealing the new vessel in a fluid-tight manner and with connections for conveying a boiling, washing or dyeing medium through the vessel.

A constructional form of the invention, which should be regarded as an example only, is shown diagrammatically in the accompanying drawing. Fig. 1 shows the new pail in perspective suspended from the hook of a crane. Fig. 2 shows in vertical section how the new pail is used for boiling, cooling and washing vegetables. Fig. 3 is a plan view of Fig. 2.

In the example shown the new vessel consists of a sheet metal pail *a* having a perforated bottom *b* and perforations *c* near the

upper rim. The vegetables or the like are placed in the pail *a*. If the vegetables are for instance to be boiled, cooled and washed, the new pail is placed, as shown in Figs. 2 and 3, into a trough-like container *i* which is divided by upright transverse walls *i*¹ into compartments *i*². The bottom *l* of each compartment *i*² has an opening *n* which is somewhat smaller than the perforated bottom *b* of the pail *a* and under which is a chamber *m* which is closed at the bottom. This chamber is provided with a closable steam supply pipe *k*, a closable water supply pipe *k*¹ and a drain cock *d*. Over the hole *n* the pail *a* is placed, preferably so that its rim *a*¹ rests on a sealing (rubber) ring *o* framing the hole *n*. The result of this arrangement is that the medium (steam or water) which is admitted under pressure through the pipe *k* or *k*¹ into the chamber *m* is forced upwards through the pail, the contents of the pail being caused to float and being consequently thoroughly penetrated and loosened up. Thus, by alternately using the pipes *k* and *k*¹, the material can be boiled, cooled and washed (or, as is for instance usual in the case of spinach, be dyed and rinsed) in direct sequence in the same vessel *a* without being shifted or transferred, if the pipes *k* and *k*¹ are connected up to the particular containers. The medium (steam or liquid) penetrating the contents of the pail from the bottom upwards passes out through the upper openings *c* in the pail and pours into the chamber *i*² of the trough which is provided at a suitable place with a drain pipe *g*.

The ring *p* for holding the sealing ring *o* in position is preferably provided as shown in Fig. 2 with an upwardly flared flange *p*¹ which facilitates the placing of the pail *a* over the opening *n*.

For the arrangement shown in Figs. 2 and 3 the existing washing troughs in preserving factories may be used, so that the new pail does not necessitate the provision

- of any elaborate new arrangements. The employment of long troughs *i*, the top plate *l* of which has several openings *n*, has the advantage that at the same time for instance in one chamber *m* the steam pipe, in the next chamber the cooling pipe and in a third compartment a cooling or dyeing pipe may be opened, so that by simply moving the pail *a* from one opening *n* to the next and so on, 10 the material can without difficulty be subjected to all the working stages. A trough or box *i*, however, the top plate *l* of which has only one opening *n* for the pail, also forms a feature of the present invention.
- 15 It should be understood that the use of the new pail *a*, *b* is not limited to apparatus of the kind shown.

What I claim is:

1. In an apparatus for boiling, washing 20 and dyeing vegetables, fruit and the like the combination with a transport vessel, having suspending or carrying means, a perforated bottom and perforations in its upper part, of a plate, an opening in the said plate, a sealing ring surrounding the said opening for supporting the rim at the bottom of the vessel and pipes for the supply of the boiling, 25 washing and dyeing media disposed below the said opening, as and for the purpose set forth. 30
2. In an apparatus for boiling, washing and dyeing vegetables, fruit and the like the combination with a transport vessel, having suspending or carrying means, a perforated 35 bottom and perforations in its upper part, of a plate, an opening in the said plate, a sealing ring surrounding the said opening for supporting the rim at the bottom of the vessel, a chamber below the said opening in the 40 plate and pipes for the supply of the boiling, washing and dyeing media to the said chamber, as and for the purpose set forth. 45
3. In an apparatus for boiling, washing and dyeing vegetables, fruit and the like, the 50 combination with a plurality of transport vessels having suspending or carrying means, a perforated bottom and perforations in their upper part of a trough, a plate forming the bottom of the trough, transverse partitions in the trough for dividing it into a plurality of compartments, an opening in the plate in each compartment, a sealing ring surrounding each opening for supporting the rim at the bottom of each vessel, a drain pipe below 55 the plate, an outflow in each compartment communicating with the drain pipe and pipes for the supply of the boiling, washing and dyeing media disposed below the said openings, as and for the purpose set forth. 60
4. In an apparatus for boiling, washing and dyeing vegetables, fruit and the like the combination with a transport vessel, having suspending or carrying means, a perforated bottom and perforations in its upper part, of 65 a plate, an opening in the said plate, a ring

surrounding the said opening, a rubber gasket in the said ring for supporting the rim at the bottom of the vessel, an upwardly and outwardly flared flange for guiding the bottom rim of the vessel, when being placed over the opening in the plate, and pipes for the supply of the boiling, washing and dyeing media disposed below the said opening, as and for the purpose set forth. 70

In testimony whereof I have signed my 75 name to this specification.

WILHELM SCHMIDT.
